CASSETTE TRANSPORT

Orville W. Larson, Elmhurst, Ill., assignor to Ampex Corporation, Redwood City, Calif., a corporation of California

Filed May 29, 1969, Ser. No. 17,417

Claims priority, application Japan Dec. 10, 1968

Term of patent 14 years

Int. Cl. D14—01, 03

U.S. Cl. D26—14

FIG. 1

FIG. 2

FIG. 1 is a front, top and left side perspective view of a cassette transport showing my new design; and

FIG. 2 is a bottom, back and left side perspective view, the right side being a mirror image of the left side.

I claim:

The ornamental design for a cassette transport, substantially as shown and described.
